UNITED STATES PATENT OFFICE.

DOMINICK CORADINO, OF JERSEY CITY, NEW JERSEY.

OIL-BURNER.

SPECIFICATION forming part of Letters Patent No. 752,042, dated February 16, 1904.

Application filed August 20, 1903, Serial No. 170,113. (No model.)

To all whom it may concern:

Be it known that I, DOMINICK CORADINO, a citizen of the United States, and a resident of Jersey City, county of Hudson, State of New Jersey, have invented certain new and useful Improvements in Oil-Burners, of which the following is a specification.

My present invention relates to oil-burners, and has for its object to provide an improved construction of a heating-burner.

A specific embodiment of my invention is shown in the accompanying drawings, in which—

Figure 1 is a front view of the improved burner with its attachments; Fig. 2, a top plan of the burner alone; and Fig. 3 a horizontal cross-section on line 3 3 of Fig. 1.

In carrying out my invention as illustrated by the drawings I employ an annular chamber A, which is formed by an outer tube or wick-tube B and an inner tube or draft-tube C. This draft-tube C is open at the bottom and is connected by two spiders D D with a centrally-located tubular guide E, open at the top and either open or closed at the bottom, as may be desired.

The annular chamber A is connected with an oil-supply in any suitable manner—for instance, by a pipe F. In the upper portion of the chamber A is arranged the oil-feed band, which takes the place of a wick. This band is adapted to be moved up and down by means of any suitable mechanism.

A spindle H carries at its upper end a cap I, adapted to extend outwardly over the oil-feed band. The cap I may be adjustably secured upon spindle H in any suitable manner, which will not be affected, however, by the heating of the cap—as, for instance, by the thread and nut construction shown.

Below the cap I a spider J is secured to the spindle H in any suitable manner, the preferable construction, however, being to provide a thread within the said spider J and screw it tightly down to the end of the thread on spindle H, said thread extending the proper distance. Upon the periphery of spider J a deflector-ring L is secured, which deflector-ring L is provided at its upper end with a contracted beveled portion L'.

A considerable length of the spindle H ex-

tends below the spider J, which lower portion of said spindle is adapted to fit loosely into the central guide-tube E, but not loosely enough to permit of appreciable lateral play 55 of said spindle. The spindle H is inserted into the central guide-tube E until the hub of spider J rests and is supported upon the upper end of said central guide-tube E, when the cap I and the deflector-ring L will be held in 60 operative position relatively to the wick and draft tubes and the feed-band as well as to the outside draft-deflector O, which forms a portion of the general construction of the burner.

It will be seen that the spindle H and the parts mounted thereon may be lifted up and out of the central guide-tube E, and this feature is very desirable, both for the reason that it enables the "spreader," as I term the 70 entire piece comprising the spindle H and parts carried thereby, to be easily removed and for the reason that when the oil-feed band is raised too high, as is often the case, it permits cap I to rise therewith, preventing the 75 crushing of the upper end of said oil-feed band by the said cap if said cap were fixed instead of movable.

Another prominent and very useful feature of this construction is the permitting of the 80 spreader to resume its normal position by gravity when the oil-feed band is again lowered, which is attained by providing the fit of the spindle H in the central guide-tube loose enough to invariably attain this result by the 85 weight of the spreader.

A desirable construction of the spreader is illustrated in Fig. 1, the spider J being fixed upon the spindle H, a section of tube K fitted over the spindle H and resting on the hub of 90 the spider J determining the distance between said spider and the cap I, the cap I apertured and threaded to screw on the spindle H to rest upon the tube-section K, and a nut M screwed down on said threaded portion of the spindle 95 against and to retain cap I.

It will be seen that the spider J being screwed down tight against the end of the thread on spindle H always holds the deflector-ring L in the same relative position to 100 spindle H and that the cap I is threaded upon spindle H, and therefore adjustable to vary

the distance between the said deflector-ring L and the cap I. The lock-nut M will fix the cap at any point upon the spindle H to which it may be adjusted; but I provide the tube-section K to determine this distance, and it may be filed off or a washer added to vary its length. Any means may be employed to regulate the distance between the deflector-ring and the cap without departing from the spirit 10 of my invention.

The cap I is provided with a series of apertures N about its central portion adjacent to the spindle H.

It will be observed that air is supplied to 15 the flame at four different points. First, a certain amount of air passes up between the outside draft-deflector O and the wick-tube B; second, an annular film of air passes through the spiders and between the draft-tube C and 20 the deflector-ring L and reaches the inner edge of the oil-feed band; third, a further supply of air passes through the spiders up through the deflector-ring L and after being first thrown inward is deflected outward by the cap 25 I, so as to cause the flame to flare outward; finally, there is also a central draft through the spiders and the apertures N in the cap I. By all these means a very complete combustion is insured and the flame given shape suitable for heating purposes by a very simply-constructed and efficient device.

By providing the apertures N in the cap I, I utilize the same conduit—namely, the channel through the spiders—for the central draft 35 as is provided for the bulk of the drafts and may vary the volume of said central draft simply by varying the size of the apertures N, the said common conduit being capable of supplying ample draft.

Another feature of my present invention is 40 the constructing of the central guide-tube E with two spiders some distance apart, which spiders may be made to fit snugly in the wick-tube B, but yet be adjustable longitudinally 45 therein or removable therefrom, which construction at the same time always insures the perfect centering of the deflector-ring L and cap I.

It is obvious that various changes may be 50 made in the details of positionment and construction without departing from the spirit of my invention.

What I claim as new, and desire to secure by Letters Patent, is—

55 1. In a burner, the combination of a draft-tube, a feed-band immediately without said draft-tube, a guide-tube mounted concentrically with said draft-tube, the outside diameter of said guide-tube being of a lesser diameter 60 than the inner diameter of said draft-tube, thus forming an annular chamber about said guide-tube, and a deflector-ring mounted upon a spider having a central spindle adapted to fit loosely in said guide-tube, said deflector-ring dividing the upper portion of said an-

nular chamber into inner and outer annular passages.

2. In a burner, the combination of a draft-tube, a feed-band immediately without said draft-tube, a guide-tube supported concentrically within said draft-tube by means of a spider frictionally engaging the inner walls of said draft-tube thus forming an annular chamber about said guide-tube, a spindle adapted to fit loosely in said guide-tube, a deflector-ring of lesser diameter than said draft-tube and greater diameter than said guide-tube mounted concentrically upon said spindle by means of a spider fast upon said spindle, and a cap of greater diameter than said feed-band concentrically mounted on said spindle above said deflector-ring to project over said feed-band, said cap provided with apertures about its central portion affording communication between said annular chamber 85 to the space above said cap, said spindle adapted to be lifted by the raising of said feed-band and to gravitate to its normal position when said feed-band is again lowered.

3. In a burner, a spreader comprising a 90 spindle, a spider mounted upon said spindle, a deflector-ring mounted upon the periphery of said spider, a section of tubing fitting over said spindle and resting on said spider, a cap having a central aperture fitting on said spindle and resting on said section of tubing, said cap provided with a series of apertures arranged about its central aperture, and a nut threaded upon said spindle and retaining said cap and section of tubing thereon.

4. In a burner, a spreader comprising a spindle, a deflector-ring mounted upon said spindle, a cap mounted on said spindle, one of said elements adjustably mounted upon said spindle to permit of the varying of the distance between them.

5. In a burner, a spreader comprising a spindle threaded throughout a portion of its length, a deflector-ring having a spider-support threaded and screwed down against the end of said thread upon said spindle, a cap threaded on said spindle and a lock-nut for fixing the position of said cap on said spindle.

6. In a burner, a spreader comprising a spindle threaded throughout a portion of its length, a deflector-ring having a spider-support threaded and screwed down against the end of said thread upon said spindle, a cap threaded on said spindle, a section of tube about said spindle determining the distance 120 between said deflector-ring and said cap, and a lock-nut for fixing the position of said cap when screwed into place.

In testimony whereof I have signed my name to this specification in the presence of two subscribing witnesses.

DOMINICK CORADINO.
